UNITED STATES PATENT OFFICE.

EDWARD J. POPE, OF HOLYOKE, MASSACHUSETTS.

PAPER-MAKING MACHINE.

1,208,000.

Specification of Letters Patent. Patented Dec. 12, 1916.

Application filed June 11, 1915. Serial No. 33,451.

To all whom it may concern:

Be it known that I, EDWARD J. POPE, a citizen of the United States, residing at Holyoke, in the county of Hampden and 5 State of Massachusetts, have invented certain new and useful Improvements in Paper-Making Machines; and I do hereby declare the following to be a full, clear, and exact 10 description of the invention, such as will enable others skilled in the art to which it appertains to make and use the same.

This invention has particular reference to the manufacture of paper on machines of the Fourdrinier type, and relates more particularly to means for producing a web of paper having a portion of lesser thickness than the major part of the web; also what is known as "deckle edged" or "feather edged" paper, and has for its object to economically 20 produce a uniform product.

The improvement appertains to an attachment for a paper making machine in which a thin section or strip in a web of paper is accomplished by applying fluid pressure to 25 the pulp fiber when distributed over the endless apron or wire web, the fluid pressure being directed and applied by adjustable elements mounted over the wire web, which operate upon the sheet of pulp product to 30 cause one or more sections of the resultant web of paper to be thinner than the main portion thereof.

The improvement also relates to means to give a finished appearance to the thinner 35 section of the web.

While embodiments of the invention are illustrated in the accompanying drawings, it is to be understood that the disclosures therein made are for the purpose of illustration only, and not as defining the limits 40 of the invention.

In the drawings: Figure 1 is a plan view of a part of a Fourdrinier machine disclosing the invention applied thereto. Fig. 2 45 is a side elevation of a part of the machine illustrated in Fig. 1. Fig. 3 is a sectional elevation through the machine of Fig. 1. Fig. 4 is an enlarged section in plan of the deckle forming frame. Fig. 5 is an enlarged 50 side elevation, partly in section, disclosing the nozzle. Fig. 6 is a view similar to Fig. 5, disclosing an attachment from the nozzle

to one of the slices. Fig. 7 is an enlarged plan view disclosing line forming rollers. Fig. 8 is an enlarged side elevation of the 55 device of Fig. 7. Fig. 9 is a detail view of rolls or disks to make the thin strip even.

The invention is designed for use in the manufacture of paper wherein the web of paper is provided with a thin strip, the 60 paper so produced being found advantageous for book making and the like.

The invention is particularly adapted for manufacturing paper having what is known as "deckle edge" or "feather edge." The 65 operation of making deckle edge or feather edge paper by machine is well known, and has been practised in a variety of ways. In some instances, the layer of pulp fiber is rendered thinner at a predetermined place or 70 line on the web by removing a portion of the pulp by suction, or by applying a jet of water to the pulp surface after it has been distributed over the endless apron or wire web of a paper making machine. It has 75 been found, however, that these methods do not produce a satisfactory or uniform product. The disadvantages in the prior methods are overcome by applying fluid pressure to the pulp fiber after it has been operated 80 upon by the slices. Line-forming devices serve to maintain the desired thinness of the material along a defined line of the pulp surface, which line-forming devices are adjustable with relation to its operative ac- 85 tion on the pulp surface. Finishing rolls may engage the material after being acted upon by the line forming device to make the thin strip formed in the web uniform and even in appearance, and produce a web 90 of paper having a well-defined portion of thinner material.

In the embodiment of the invention illustrated in the accompanying drawings, the machine is provided with a rail frame 1, 95 which serves to support the various features of the bed of the machine, including the deckle frames 2. These frames 2 are shown supported by the rods 3 which in turn are secured to the supports 4 at each side of the 100 frame.

An endless apron 5, shown in the form of the wire cloth, is mounted on the rolls 6, 7, the roll 6 being shown as a breast roll. The

wire cloth or apron 5 may also be supported by the rolls 7 positioned at the bed of the machine, one of which rolls is illustrated in Fig. 3 as being supported in the bearings 8 carried by the frame. The bed of the frame is mounted upon uprights 9. The deckles 10 are shown carried by the pulleys 11, the larger of which pulleys is positioned adjacent the flow box 12 from which the pulp is conveyed to the wire cloth 5. A plurality of slices 13 having adjusting means 14 at the central portion thereof, are shown slidably mounted in grooves 15 over the bed of the machine.

15 The line-forming devices are mounted upon the bed of the machine upon suitable cross pieces 16, a plurality of which are shown arranged parallel to each other in Fig. 1. These cross pieces are supported by the standards 17 on each side of the machine, which standards may be bolted to the side rails A as indicated at 18 in Fig. 2. These cross pieces 16 serve to support the line-forming devices over the bed of the machine.

Any suitable number of line-forming devices may be employed, but in the drawings only two are shown, which are arranged parallel to each other and to extend longitudinally of the bed of the machine. Each of the line forming devices is shown as comprising a forward end 19, which may be of greater height than the rearwardly extended portion 20 thereof. This forward section is shown provided with an inclined front wall 21 to produce a receptacle 22, the walls of which are inclined to form a contracted lower end 23 which terminates in a nozzle indicated at 24. The front wall 21 is shown beveled on each side of its lower end so that it terminates in an apex adjacent the nozzle. This receptacle formed at 22 is shown open in the drawings, although it is obvious that a cover 25 may be applied thereto if desired, to employ the chamber in conjunction with fluid under pressure, such as air or steam. It is obvious that the means to convey fluid under pressure, such as air or steam, and which is indicated at 26, may extend through this forward portion of the line-forming device and terminate at the nozzle 24, thereby eliminating the chamber at 22. It is desired, however, to employ in one form of the machine, any suitable fluid, such as water, which may fill the chamber 22, and which is not jetted into the surface, but merely forces against the same by its weight. Extending from the enlarged portion 19 of the line-forming device, are a plurality of members 27 which are shown arranged parallel to each other, and as a continuation of the side walls of the chamber 22. These members 27 serve to prevent the pulpy substance from flowing back from the bed of the material into the reduced part thereof,

which is formed by the nozzle, and the parallel members 27 of each of the line-forming devices are adjustably mounted with relation to the bed of the frame.

In the drawings, the nozzle or enlarged end 19 is shown integral with the parallel members 27, and the whole structure is shown secured to adjusting and supporting elements 28 which are suspended from the cross pieces 16 and are slidably mounted on said pieces whereby the parallel members 27 of each of the line-forming devices may be transversely adjusted at various positions over the bed. The elevation of these parallel members is controlled by a hand wheel 29 which is mounted upon the threaded portion 30 of the supporting element 28. It is obvious therefore, that the forward portion of the line-forming device may be positioned closer or farther away from the bed or pulp than is the rear portion, by the manipulation of the hand wheels 29.

It may be found desirable to mount the line-forming devices in juxtaposition to one of the slices 13, and, if desired, the forward end of the line-forming device may be connected with one of the slices 13 by a thin strip 31 which is shown in Fig. 6 as extending from the front wall 21 of the head of the line-forming devices, and extending forwardly, and upwardly terminating in a retaining flange 32 which is adapted to engage the opposite face of the adjacent slices 13. However, the nozzle end of the line-forming device may be spaced away from the adjacent slice 13, such adjustment being effected by the slotted section 33 of the line former and the elements 25, 29.

At the rear of the line-forming devices is provided suitable means to give a finished appearance to the thinner section of the web of paper. One of the cross rods or supporting rods 40 of the frame may be provided with a plurality of collars 34 slidably and adjustably mounted therein, and retained in the adjusted positions by any suitable means, such as the screws 35. The collars 34 may be provided with suitable means 36 to support arms 37 which carry narrow rollers or disks 38. The engaging surface of the rollers 38 may be covered with wire cloth, or any other suitable material to engage the pulpy material where it has been thinned out by the line-forming devices to give a better finish and make the portion of lesser thickness in the web of more even appearance. The arms 37 may be hinged to their supports at 39, or the connection may be a rigid one, as desired.

If desired the rolls 38 may be mounted directly upon the element 40, which may be a rotatable shaft for the rolls 38 and deckle pulleys 11, and these rollers 38 may be provided with bushings 41 having means, such as the screws 45 to secure the rollers in

longitudinally adjusted positions on the shaft 40, as in Fig. 9. Where the machine is arranged to make but one grade of paper, the finishing devices for the thinner sections 5 may be permanently mounted on the machine. For example, the finishing rollers 38 may be entirely dispensed with and in lieu thereof the dandy roll 42 may be provided with a narrow strip, or several strips of 10 wire cloth, or other suitable material, indicated at 43, to contact with the pulp at the thin part formed by the line formers.

In the operation of the machine when forming paper having a thin strip in the 15 web thereof, the parallel members 27 are adjusted at the proper point above the wire cloth 5 to prevent the pulp from flowing into the space between the parallel members 27 of each of the line-forming devices to the 20 extent which it flows under the slices 13. The chamber 22 may be filled with water, or a stream of water, air or steam may run into the chamber, the nozzle 24 of which allows the force of water, air or steam to regulate the amount of pulp which shall flow in 25 alignment with the space between the parallel members 27. The thickness of the pulp to be passed between the parallel members 27 can be regulated by the amount of pressure 30 of water, air or steam which is admitted through the nozzle 24 and also by the line finishing devices 38 or 43. In the construction of Fig. 6, the strip of pulp may also be obtained by the extended strip 31 35 which projects under the slice 13, in which event the fluid pressure may be eliminated.

In forming the deckle edge, the line-forming device 27 may be adjusted closer together over the bed of the machine and the 40 amount of fluid pressure used may be adjusted to secure the desired result so that before the web of paper is entirely finished, the web will separate at the thin place formed by the line-forming devices and 45 thereby present an unfinished edge to the web of paper to imitate paper made by the hand process.

Where a feather edge is desired, the line-forming devices are adjusted to allow but a 50 small amount of the pulp to enter at the forward ends 19 thereof, while the rear ends 44 may be elevated from the bed to a greater extent than the forward end to permit the pulp to flow in from each side of the parallel members 27 of the line-forming frames, thus making the web of paper provided with a portion which is thinner at the center than at each edge, which was formed by the parallel members 27, by reason of the fact that 55 the pulp material will flow in between the parallel members 27 as the material is passed over the bed of the machine. The finished product will separate at the line so formed, making each edge thereof tapered.

Having thus described my invention, what

I claim as new and desire to secure by Letters Patent is:

1. In a machine of the class specified, the combination with an apron, of means to direct fluid pressure against material carried by said apron formed as a part of a line-forming element comprising an elongated bar to engage the material carried by the apron after it has been acted upon by fluid pressure. 75

2. In a machine of the class described, the combination with an apron, of means to direct fluid pressure into contact with material on the apron and a stationary line-forming element adjustably mounted with relation to 80 the apron to engage the material on the apron after it has been acted upon by fluid pressure.

3. In a machine of the class described, the combination with an apron, of means to direct fluid pressure into contact with the material on the apron to reduce the thickness of the material, and a stationary line-forming element adjustable longitudinally with 85 relation to the surface of the apron. 90

4. In a machine of the class described, the combination with an apron, of means to exert pressure on the material of the apron to reduce the thickness of material, and a stationary line-forming element adjustable longitudinally and transversely with relation to 95 the surface of the apron.

5. In a machine of the class described, the combination with an apron, of means to exert pressure on the material carried by the apron to reduce the thickness of said material, and a stationary line-forming element comprising elongated parallel members which are adjustable longitudinally and transversely with relation to 100 105 the surface of the apron.

6. In a machine of the class described, the combination with an apron and a slice adapted to be positioned transversely thereof, of means to direct fluid pressure into 110 contact with the material on the apron to reduce the thickness of the material, said means being arranged in juxtaposition to said slice, and a line-forming element for each fluid pressure means comprising a plurality of elongated members extending longitudinally of said apron from said fluid pressure means. 115

7. In a machine of the class described, the combination with an apron and a slice adapted to be positioned transversely thereof, of means to exert pressure on material carried by the apron to reduce the thickness of the material, means to connect said pressure means with said slice and to engage the material on the apron, and a line-forming element comprising a plurality of elongated members extending longitudinally of said apron from said pressure means. 120 125

8. In a machine of the class described, the 130

- combination with an apron, of stationary line forming means having as a part thereof a fluid chamber provided with a material contacting nozzle to direct fluid pressure into contact with material on the apron to reduce the thickness of material which is thereafter engaged by the line forming means. 5
9. In a machine of the class described, the combination with an apron and a slice, of fluid pressure means having a material contacting nozzle and a strip extending from said nozzle to the lower edge of said slice to contact with the material prior to its engagement by fluid from said nozzle. 10
15. 10. In a machine of the class described, the combination with an apron of a fluid pressure device having a material-contacting nozzle, a line-forming element formed as a part of said nozzle, said element being 20 divided longitudinally to produce a plurality of line-forming members extending from the fluid contacting-nozzle to maintain the material of the apron in its relative thickness as formed by said nozzle. 25
11. A device of the class described comprising a line-forming element for paper making machines having a fluid receptacle provided with a contracted lower end terminating in a forwardly and downwardly 30 directed nozzle, and a plurality of spaced members extending rearwardly of said nozzle. 35
12. A device of the class described comprising a line-forming element for paper machines having a fluid receptacle near one end thereof provided with a contracted lower end terminating in a broad mouthed nozzle, and a plurality of spaced members extending rearwardly of said nozzle substantially in alinement with the outer edges thereof. 40
13. A device of the class described comprising a line-forming element for paper making machines having a fluid receptacle 45 provided with a contracted lower end terminating in a forwardly and downwardly directed nozzle, and a plurality of spaced members extending rearwardly from said nozzle to engage pulp material of a paper making machine after a part of said material has been treated by substances passing through said nozzle to maintain a defined line in the material of substantially the width and thickness produced by said nozzle. 50
55. 14. In a machine of the class described, the combination with an apron, of a line-forming device, adjustably mounted longitudinally and transversely with relation to said apron, said line-forming device having
60. a nozzle and a plurality of spaced members extending rearwardly of said nozzle which are adapted to engage the material carried by the apron after a part of said material has been treated by substance passing through said nozzle. 65
15. In a machine of the class described, a movable element for paper-making material, line-forming means to engage the material on the movable element, and finishing means for that part of the material which 70 has been engaged by the line-forming means. 16. In a machine of the class described, the combination with an apron for paper-making material, of line-forming means 75 over the apron to engage the paper-making material, and line-finishing means positioned at the rear of the line-forming means. 17. In a device of the class described, the combination with an apron for paper-making material, of line-forming means adjustable transversely over said apron, and line-finishing means adjustable transversely 80 with relation to the apron and in alinement with the line-forming means. 85
18. In a machine of the class described, the combination with an apron for paper-making material, of means to exert pressure on the paper-making material to reduce the thickness of the material and form a line 90 of thinner material longitudinally of the web of paper, and means positioned to engage the material of lesser thickness to clearly define the line of thinner material in the finished product. 95
19. A machine of the class described having a plurality of line-forming elements capable of adjustment longitudinally and transversely of the machine, each of said line-forming elements comprising a receptacle at one end thereof, terminating in a nozzle having a broad mouth and a plurality of parallel spaced members connected to the nozzle and receptacle to engage pulp material and maintain a defined line in the material after the pulp material has been subjected to the action of substances passing through the nozzle. 100
105. 20. In a machine of the class described, a plurality of line-forming elements capable of adjustment longitudinally and transversely of the machine, each of said line-forming elements comprising a nozzle and a plurality of parallel spaced members connected to the nozzle, said spaced members 110 having substantially sharpened material-engaging edges. 115
